H. N. HEILMAN.
COUPON CUTTING MACHINE.
APPLICATION FILED JAN. 24, 1919.

1,414,128.

Patented Apr. 25, 1922.

INVENTOR.

Henry N. Heilman

UNITED STATES PATENT OFFICE.

HENRY N. HEILMAN, OF ST. LOUIS, MISSOURI.

COUPON-CUTTING MACHINE.

1,414,128.

Specification of Letters Patent. Patented Apr. 25, 1922.

Application filed January 24, 1919. Serial No. 272,825.

To all whom it may concern:

Be it known that I, HENRY N. HEILMAN, a citizen of the United States, residing at St. Louis, Missouri, have invented a new and useful Coupon-Cutting Machine, of which the following is a full, clear, and exact description.

My invention relates to improvements in paper cutting machines, and particularly to a manually-operated machine which is designed and constructed so as to cut with a single stroke a number of coupons from bonds, or the like, the principal object of my invention being to provide a relatively, simple easily operated machine which may be easily and cheaply manufactured and which will be very effective in performing its intended functions.

Further objects of my invention are to provide a coupon cutting machine with an angular knife, that is, a knife with one part of the blade disposed at right angles to the other part so that, at one stroke, the coupon is cut from the bond to which it is attached, along one side and end, and, further, to provide on the table of the machine adjustable stops or guides which may be utilized for correctly locating the bonds and coupons with respect to the knife.

With the foregoing and other objects in view, my invention consists in certain novel features of construction and arrangement of parts hereinafter more fully described and claimed and illustrated in the accompanying drawings in which—

Fig. 1 is front elevational view of my improved machine.

Fig. 2 is a plan view of the machine.

Fig. 3 is a vertical section taken approximately on the line 3—3 of Fig. 2.

Fig. 4 is a perspective view of the knife or cutting element made use of in my improved machine.

Referring by numerals to the accompanying drawings, 10 designates a base or bed plate which serves as a table on which the bonds or like papers are positioned, and projecting upwardly from the sides of said base are posts 11, in the inner faces of which are formed vertically disposed grooves 12.

Connecting the upper ends of posts 11 is a rail 13 provided at its center with a vertically disposed cylindrical housing 14. Pivotally mounted on a transverse pin 15 in the upper portion of this housing is one end of a hand lever 16, and interposed between said

lever and the rail 13 is a compression spring 17. Pivotally connected to hand lever 16 near the point where it is pivoted to the housing 14 is the upper end of a link 18, the lower end thereof being pivotally connected to the upper end of a plunger 19. This plunger is adapted to move vertically through the lower portion of the housing 14 and the lower end of said plunger is secured to a bar 20 which is positioned beneath rail 13.

The ends of this bar 20 are arranged for sliding movement in the grooves or guide slots 12, and fixed to and projecting outwardly from the central portion of said bar is an arm 21. Secured to this arm and to the bar 20 to one side thereof is the knife or cutting element of the machine, said knife comprising a blade or body portion 22, with one end of which is formed integral a blade 23, the same being disposed at right angles to the blade or body 22. The lower edges of the blades 22 and 23 are beveled and sharpened to form cutting edges.

Formed in the top of base 10 and immediately below the blades 22 and 23 are grooves 24, and positioned therein are strips 25 of wood or like material. Formed in the base 10 near its side and rear edges are slots 26 and adjustably arranged therein are screws 27, to the upper ends of which are secured guide rails 28, the same serving to assist in correctly locating on the base or table the sheets from which the coupons are to be cut.

It will be understood that the spring 17 maintains handle 16 in an elevated position, consequently, bar 20 and the angular knife carried thereby are held at their upper limit of movement. The bonds from which the coupons are to be cut are placed in a pile, one on top of another and said bonds are now placed on the table against the rails 28, and which latter have been properly adjusted. Handle 16 is now pressed downward and as a result link 18 will force plunger 19, bar 20 and blades 22 and 23 forward, which action forces the edges of said blade through the sheets positioned on the table and a corresponding series of coupons will be cut or severed from said sheets, the lines of severance being along one side and end of each coupon. Thus by my improved form of cutting blade a coupon is cut from the bond or sheet to which it is attached, along two edges at the same time and as a result

much time and labor can be saved in the operations incident to the cutting of coupons and the like.

Obviously, minor changes in the details 5 of construction of my improved machine may be made without departing from the scope of the appended claims.

I claim as my invention—

1. In a coupon cutting machine, a table, 10 uprights thereon, a bar arranged for vertical movement between said uprights, an arm projecting outwardly from said bar and at right angles thereto, a blade secured to said bar and arm, said blade having portions arranged at right angles to each other there 15 being grooves formed in the table directly below the cutting edges of the blades strips of relatively soft material positioned in said grooves and adjustable guides arranged on 20 said table to the sides and rear of said strips of material.

2. In a coupon cutting machine, a table, 25 uprights thereon, a bar arranged for vertical movement between said uprights, an arm projecting outwardly from said bar and at right angles thereto, a blade secured to said bar and arm, said blade having portions arranged at right angles to each other, means 30 for moving said bar vertically between said uprights there being grooves formed in the table directly below the cutting edges of the blades strips of relatively soft material positioned in said grooves and adjustable guides arranged on said table to the sides 35 and rear of said strips of material.

3. In a coupon cutting machine, a table, 40 adjustable work guides arranged on said table adjacent to its side and rear edges, standards on said table, which standards are provided with guide grooves, a bar arranged 45 to move vertically between said standards, and with its ends operating in said grooves, a blade having portions disposed at right angles to each other with one portion secured to said bar and the other portion secured to said arm.

4. In a coupon cutting machine, a table, 50 uprights thereupon, a rail supported by said uprights, a plunger arranged for operation in said rail, a bar arranged for vertical move-

ment between said uprights, an arm projecting outwardly from said bar and at right angles thereto, a blade secured to said bar and arm, said blade having portions arranged at right angles to each other means 55 for actuating said plunger there being grooves formed in the table directly below the cutting edges of the blades strips of relatively soft material positioned in said grooves and adjustable work guides arranged on said 60 table to the sides and rear of said strips of material.

5. In a coupon cutting machine, a table, 65 wooden strips inserted in the top of said table and disposed at right angles to each other, adjustable work guides on the table and disposed immediately to the sides and rear of said wooden strips, a member arranged for vertical movement above the table, and a blade carried by said member, 70 said blade having portions arranged at right angles to each other, the lower edges of which blades are adapted to engage the wooden strips when moved downward to engage the work positioned on top of the table. 75

6. A coupon cutting machine comprising a bed-plate in the top of which are formed grooves disposed at right angles to each other, wooden strips removably positioned in said grooves, posts at the sides of said bed plate, said posts being provided with grooves, a bar having its ends arranged for sliding movement in said grooves, an arm projecting outward from the center of said bar, a blade having portions arranged at 85 right angles to each other, one portion being fixed to the bar and the other portion fixed to the arm, the cutting edge of which blade is adapted to engage the wooden strips when said blade is moved downward to engage the work, adjustable work guides on the table, and a spring held fulcrumed handle connected to the bar for moving the same 90 downward to carry the blade through the work. 95

In testimony whereof I hereunto affix my signature this twentieth day of January, 1919.

HENRY N. HEILMAN.
